UNITED STATES PATENT OFFICE.

CHARLES W. SEAMAN, OF NEWBURGH, NEW YORK.

DESIGN FOR TONGS.

49,863.

Specification for Design.

Patented Nov. 7, 1916.

Application filed September 3, 1915. Serial No. 48,884. Term of patent 3½ years.

To all whom it may concern:

Be it known that I, CHARLES W. SEAMAN, a citizen of the United States, residing at Newburgh, county of Orange, and State of New York, have invented a new, original, and ornamental Design for Tongs, of which the following is a specification, reference being had to the accompanying drawing, forming part thereof.

The figure is a perspective view of the tongs illustrating my new design.

I claim:—

The ornamental design for tongs, as shown.

CHARLES W. SEAMAN. [L. S.]
